UNITED STATES PATENT OFFICE.

ALBEN E. LUNDELL, OF NEW YORK, N. Y., ASSIGNEE TO WESTERN ELECTRIC COMPANY,
INCORPORATED, OF NEW YORK, N. Y., A CORPORATION OF NEW YORK.

TELEPHONE-EXCHANGE SYSTEM.

1,276,549.

Specification of Letters Patent. Patented Aug. 20, 1918.

Application filed December 26, 1916. Serial No. 139,512.

To all whom it may concern:

Be it known that I, ALBEN E. LUNDELL, a citizen of the United States, residing at New York, in the county of Bronx and State of New York, have invented certain new and useful Improvements in Telephone-Exchange Systems, of which the following is a full, clear, concise, and exact description.

This invention relates to telephone exchange systems, and particularly to circuit arrangements for automatic telephone exchanges.

It is the object of this invention to provide an improved telephone system in which switching means, by which connections may be established between calling lines of various character and a called line, are variably operable for performing their connecting function, the various operations of the switching means being determined by the class or character of the calling line.

In semi-mechanical telephone exchange systems it is customary to provide, in association with one of a train of switches by which connection may be established between two lines, such as the connector switch, an interrupter by means of which the controlling operator's supervisory lamp is flashed in case the desired line is found busy. In case it is required to combine such semi-mechanical systems with a full-automatic system, it will be necessary to control the operation of said connector switch from a subscriber's station. In this case, in view

of the fact that the calling station is not equipped with supervisory lamps, instead of a visual busy signal, an audible busy signal is given for the purpose of conveying to the controlling party information of the busy condition of the desired line.

The apparatus arranged to produce the audible busy signal is also associated with the mentioned connector switch. The two busy signaling apparatuses are permanently associated with the connector switch, and for this reason, in the latter mentioned case, due to the impulses sent by said interrupter, the connection established under the control of the subscriber may be mutilated. The sending of such impulses might result, for instance, in the undue actuation of a call register or meter associated with the line of a full automatic subscriber.

In order to prevent such interference with the proper operation of the system, accord-

ing to the present invention, means are provided whereby, depending on the character of the line calling (semi-mechanical or full-automatic), a plurality of busy signaling means permanently associated with a selectively operable switching device are alternatively rendered effective.

In the drawings, Figures 1 and 2, placed side by side, diagrammatically represent a semi-mechanical telephone system; and Fig. 3, taken together with Fig. 2, represents a full automatic telephone system.

The automatic switches shown in the drawings may be of a structure similar to that shown in Patent 1,123,696 to E. B. Craft and J. N. Reynolds. The sender cord finder switch, indicated in Fig. 1, will ordinarily be provided with but a single set of brushes.

The sequence switches, shown in the drawings, may be similar to that disclosed in Patent 1,127,808. The numerals which appear adjacent to the sequence switch contacts, diagrammatically represented in various portions of the drawings, indicate the positions of the sequence switch at which these contacts are closed, with the exception that the controlling contacts, one of which appears immediately above the motor magnet of each of the sequence switches, are opened only at the positions indicated by the numerals adjacent thereto and, therefore, the sequence switch can stop in only these positions.

The circuits for controlling the operations of the various selector switches, and of the sender, are not disclosed in detail. The senders shown in the lower portions of Figs. 1 and 3, are of the revertive-impulse type disclosed in Patent 1,168,319 to A. E. Lundell. The sender shown in Fig. 1 and the various selector switches are operable in the same manner as disclosed in the mentioned Patent No. 1,168,319. The control of the sender shown in Fig. 3 is performed by a full automatic subscriber. This control may be exercised in the manner disclosed in Patent 1,157,881, to F. R. McBerty, or in the manner disclosed in an application of Reeves and Lundell, Serial No. 72,908, filed January 19, 1916.

The structure and arrangement of the senders and selector switches has no bearing on the present invention, and instead of the senders and selectors described in the

above mentioned patents, any other rever-
5 tive impulse sender or selector switch may
be used without departing from the spirit
of the invention. Obviously, instead of a
reveritive impulse sender, an impulse sender
may be used by means of which the selector
switches are directively set.

Only a general outline of the sender ar-
10 range shown in the mentioned patents
is given in the drawings, and the operating
positions of the sequence switches shown in
Figs. 1 and 3 are different from those used
in the cited patents. With reference to the
15 sender shown in Fig. 1, the cord finder F,
shown in Fig. 2 of the patent, is represented
at 139, only two wipers, 138 and 126, and two
terminals adapted to be engaged by the
wipers being shown. These wipers corre-
20 spond to the third and fifth wipers of the
cord finder shown in the mentioned patent.

In order to simplify the circuit shown in
Figs. 1, 2 and 3 of the patent, a single cir-
25 circuit is shown extending between the sender
and the controlling apparatus of the selec-
tor 115 where a plurality of circuits are
shown in the patent. Only one sequence
30 switch 118 is shown in Fig. 1 for performing
functions which are usually performed by
two sequence switches. This sequence
switch therefore is a combination of the se-
35 quence switch 300 and 400 shown in the
patent. Under the control of a circuit in-
cluding the conductor leading to the left-
hand contact of sequence switch spring 117,
40 the sequence switch 118 may be moved out of
position 1. Sequence switch contact 116 is a
combination of sequence switch contacts 206
and 208 of the patent, the mentioned con-
45 ductor corresponds to conductor 305, and se-
quence switch spring 117 to sequence switch
spring 304 of the patent. Relay 119 cor-
responds to relay 309 of the patent. In
order to simplify the circuits, this relay is
50 shown as controlling the movement of se-
quence switch 118 out of position 1, although
relay 309 does not perform this function.
Instead of the energizing circuit including
the right-hand winding of relay 309 of the
55 patent, and the holding circuit including the
left-hand armature and winding of relay
309, a single circuit is shown including the
right-hand contact of sequence switch spring
117, and sequence switch spring 122. The
60 conductor by means of which the two last
mentioned sequence switch contacts are in-
terconnected, corresponds to conductor 317,
and sequence switch spring 122 to spring
209 of the patent. Relay 110 corresponds to
65 relay 403, and relay 129 to relay 402. The
conductor leading to wiper 126 corresponds
to conductor 244, sequence switch spring
125, to spring 215, and relay 123, to relay
212 of the patent. The conductor 235 and
70 sequence switch contact 234 of the patent,
which are used when sending impulses be-

yond the selector shown in Fig. 1 of the pat-
75 ent, are left out, the last mentioned conductor
and sequence switch spring 125 being
used for this purpose. The conductor lead-
ing to wiper 138, by means of which sequence
switch 113 may be moved into the talking
position, corresponds to conductor 245 of the
patent and sequence switch spring 137 to se-
quence switch spring 429 of the patent.

Establishment of a semi-mechanical condition. 75

A subscriber at station 100 desiring to ob-
tain a connection with a subscriber at sta-
80 tion 200 removes his receiver from the switchhook,
whereupon his line is extended in any well-known manner to a cord circuit 101. The answering supervisory relay SR becomes energized. A controlling operator at whose position the cord circuit 101 is 85 provided, receives the order of the calling subscriber and communicates with a B operator, whose controlling apparatus consists of the sender, by means of a well-known order wire circuit (not shown). The B operator 90 instructs the A operator to extend the line through an idle trunk 102, 103 and 104, whereupon the A operator inserts plug 105 into the jack 106, in which the assigned trunk terminates at her board. A circuit is 95 closed thereupon from grounded battery through the winding of a relay 107, the sleeve contacts of plug 105 and jack 106, conductor 104, and the winding of a slow-to-release relay 108, to grounded battery. 100 Relay 107 closes a circuit from ground through its armature and front contact, the back contact and armature of a calling supervisory relay SR' and a supervisory lamp SL, to grounded battery, whereupon this lamp is lighted. Relay 108 closes a circuit from ground through its armature and front contact and the winding of a relay 109 to grounded battery, causing thus the energization of this relay. 105

The B operator writes down the number of the desired subscriber on her keyboard (not shown) determining thus the operation of the counting relays. In the drawings only the zero counting relay 110 is indicated. The B operator depresses also an assignment key 111, closing thus a circuit from ground through the contact of this key, the upper contact of a sequence switch spring 112, and the power magnet of a sequence switch 113, to grounded battery. The sequence switch is moved out of position 1 and under the control of its normal contact 114 into position 13. While the sequence switch is moving from position 1 to 125 position 13, the setting of a selector switch 115 is accomplished under the control of the sender, this sender being connected to the controlling circuit of the selector 115 by means of a cord finder 139 in the same 130

manner as described in the mentioned patent to A. E. Lundell. When the sequence switch 113 reaches position 2 a circuit is closed from ground through a sequence switch contact 116, the left-hand contact of a sequence switch spring 117 (controlled by a sequence switch 118), and the winding of a relay 119, to grounded battery. Relay 119 closes a circuit from ground, through its 5 armature and front contact, the left-hand contact of a sequence switch spring 120, and the power magnet of sequence switch 118, to grounded battery, whereupon the sequence switch 118 is moved out of position 1 and under the control of its normal spring 121, into position 13. While the sequence switch 118 is moving from position 1 to position 13 the above mentioned setting of selector switch 115 is controlled by the sender. 10 When the sequence switch 118 moves out of position 1, the relay 119 is held energized by a circuit extending from grounded battery, through its winding, the right-hand contact of sequence switch spring 117, and the contact 15 of a sequence switch spring 122, to ground.

As soon as sequence switch 113 reaches position 12 a circuit is closed from grounded battery through the winding of a relay 123, the upper left-hand contact of a sequence switch spring 124, a sequence switch contact 125, cord finder brush 126, a sequence switch contact 127, a resistance 128, windings of a stepping relay 129, and the back 20 contact and armature of the zero counting relay 110, to ground. Relay 123 becomes energized and closes a locking circuit for itself through its right-hand front contact and armature, and the lower contact of sequence switch spring 124. Relay 123 closes also a circuit from ground, through its left-hand armature and front contact, the lower contacts of a sequence switch spring 130, a selector wiper 131, a conductor 200, the 25 upper right-hand and lower left-hand contacts of a sequence switch spring 201, and the winding of a relay 202, to grounded battery. Relay 202 closes a circuit from ground, through its left-hand armature and front contact, the upper right-hand and lower left-hand contacts of a sequence switch spring 203, and the winding of a relay 204, to grounded battery. Relay 204 becomes energized and closes a locking circuit 30 for itself from grounded battery through its winding, right-hand front contact and armature, a resistance 205, a conductor 206, a selector wiper 132, a resistance 133, and the upper contact of a sequence switch spring 134, to ground. The relay 204 closes also a circuit from ground, through its left-hand armature and front contact, the upper right-hand contact of a sequence switch spring 207, and the power magnet of a sequence switch 35 208, to grounded battery.

Sequence switch 208 is moved out of position 1, and, under the control of its normal spring 209, into position 6. While the sequence switch 208 is moving through the positions 2, 3, 4 and 5, and before the sender 70 sequence switch 118 reaches position 13, the connector 210 is controlled in accordance with brush tripping impulses, and impulses representing the tens digit of the desired subscriber's number. 75

As soon as the sequence switch 208 moves out of position 1 the originally traced circuit of relay 202 is opened, but this relay remains energized by current flowing through a circuit traceable from grounded battery through 80 its winding, the upper contact of a sequence switch spring 211, the right-hand front contact and armature of relay 202, and the upper contacts of sequence switch spring 201 to ground at the left-hand armature of relay 123. This ground is also extended through the lower contact of sequence switch spring 211, conductor 212, and winding of a magnet 213, to grounded battery. By attracting its armature, magnet 213 presses a 85 brush rod 214 of the connector 210 against a roller 215 constantly rotating in the direction indicated by the arrow. Whenever a brush 216, carried by rod 214, engages the conducting plate 217, a circuit is completed 90 from ground, through the left-hand armature and front contact of relay 202, the upper left-hand contact of a sequence switch spring 218, a conductor 219, brush 216, conducting plate 217, a conductor 220, the contact of a sequence switch spring 221, the upper contact of a sequence switch spring 222, conductor 223, selector wiper 135, the right-hand contacts of sequence switch 95 spring 124 and the right-hand armature, 100 front contact and winding of relay 123, to grounded battery. Due to the closure of this shunt path to the winding of relay 123, the stepping relay 129, which was energized in series with relay 123, becomes deener- 105 gized and permits the actuation of the first counting relay, as determined by the setting of the units keys in the operator's keyboard. The above traced shunt path is opened as 110 soon as the wiper 216 engages an insulating segment 224 in the conducting plate 217, and thus the relay 129 is permitted to reenergize. After the connector 210 has been moved in an upward direction by a required number 115 of steps, the counting relay 110 becomes energized and opens in its back contact the circuit of relays 129 and 123, whereupon these relays become deenergized. The relay 110 closes a circuit through its front contact and sequence switch contact 136, for 120 moving the sequence switch 118 out of position 13 and into position 16, whereupon a circuit is closed from ground through a sequence switch contact 137, cord finder wiper 138, the lower contact of sequence switch 130

spring 112 and the power magnet of sequence switch 113, to grounded battery, for moving this sequence switch out of position 13 and into position 14.

5. In response to the deenergization of relay 123, relay 202 and magnet 213 become deenergized, whereupon the connector is arrested with its wipers 229, 230, 231 on the terminals of the desired line.
10. In response to the deenergization of the relay 202 a circuit is closed from ground, through the upper left-hand and lower right-hand contacts of sequence switch spring 203, and the power magnet of sequence switch 208, to grounded battery for moving this sequence switch out of position 6, whereupon the sequence switch is moved under the control of its normal contact 209 toward position 14.
15. In case the line of the desired subscriber is idle, full battery potential exists on test terminal 225 of this line. As soon as the sequence switch 208 reaches position 8 a circuit is closed from ground, through the high resistance lower winding of a marginal test relay 226, the lower contacts of a sequence switch spring 227, the low resistance upper winding of the relay 226, a sequence switch contact 228, test wiper 229, terminal 225, and the winding of a cut-off relay CO of the desired line, to grounded battery. Relay 226 becomes energized and closes a circuit from ground, through its upper armature, front contact and low resistance winding to grounded battery, at the cut-off relay CO, reducing thus the potential on the multiples of test terminal 225 for preventing the seizure of this line by another connector switch 210 in a manner to be herein-25 after set forth. The sequence switch 208 will not be arrested in position 14, because as soon as it reaches this position it will be driven into position 16 by current flowing from grounded battery through its power magnet, lower right-hand contact of sequence switch spring 207 and the lower front contact and armature of relay 226, to ground.

As soon as the sequence switch 113 reaches position 14 a circuit is closed from grounded battery, through the power magnet of sequence switch 113, left-hand contact of a sequence switch spring 140, the front contact and armature of relay 109, and the lower contact of sequence switch spring 134, to ground. The sequence switch 113 is thereupon moved into position 16. When it reaches this position, a circuit is closed from grounded battery through a sequence switch contact 141, the armature and back contact of a marginal relay 142, the back contact and armature of a relay 143, the winding of a relay 144, a sequence switch contact 145, and the front contact and armature of relay 108, to ground. Relay 144 becomes en-

ergized. Relay 143 cannot become energized in parallel with the relay 144, due to the fact that its winding is short-circuited through the armatures and back contacts of relays 142 and 143. Upon the energization of relay 144 a circuit is closed from ground through a ringing machine 146, the winding of relay 142, a sequence switch contact 147, the lower front contact and armature of relay 144, a sequence switch contact 148, selector wiper 135, conductor 223, the right-hand contacts of sequence switch spring 222, connector wiper 230, the bell at the called substation, connector wiper 231, the right-hand contacts of sequence switch spring 201, conductor 200, selector wiper 131, the right-hand contacts of sequence switch spring 130, and the upper armature and front contact of relay 144, to ground. The bell at the called substation is actuated and as soon as the called subscriber removes his receiver from the switchhook the marginal relay 142 becomes energized, opens the circuit of relay 144 and the short circuit around the winding of relay 143, whereupon this relay becomes energized and short-circuits relay 144. The energizing circuit of relay 143 may be traced in the same manner as that of relay 144.

In response to the removal of the switchhook at the called substation, the supervisory relay SR' becomes energized and opens a circuit of lamp SL, whereupon this lamp is extinguished.

When the calling and called subscribers desire disconnection and restore their receivers to the hook switches, the circuits of the supervisory relays SR and SR' are opened. Due to the deenergization of relay SR', the lamp SL is again lighted, whereupon the A operator removes plug 105 from jack 106. Relays 107 and 108 become deenergized. The lamp SL is extinguished, and relay 109 becomes deenergized and closes a circuit from grounded battery, through the winding of a relay 150, the back contact and armature of relay 109, and the lower contact of sequence switch spring 134, to ground. The relay 150 becomes energized and after a certain time interval (this relay being slow to pull up) it closes a circuit from ground, through its front contact and armature, the right-hand contact of sequence switch spring 140, and the power magnet of sequence switch 113, to grounded battery, for moving this sequence switch out of position 16 and into its normal position. While the sequence switch is moving to its normal position the selector 115 is released to normal. Upon the deenergization of relay 108, relay 143 also becomes deenergized.

Upon the restoration of selector 115, relay 204 becomes deenergized and closes a circuit from ground, through its left-hand armature and back contact, the upper left-hand contact of sequence switch spring 207, and the front contact and armature of relay 144, to ground. The lamp SL is again lighted, whereupon the A operator removes plug 105 from jack 106. Relays 107 and 108 become energized. The lamp SL is extinguished, and relay 109 becomes energized and closes a circuit from ground, through its front contact and armature, the right-hand contact of sequence switch spring 140, and the power magnet of sequence switch 113, to grounded battery, for moving this sequence switch out of position 16 and into its normal position. While the sequence switch is moving to its normal position the selector 115 is released to normal. Upon the deenergization of relay 108, relay 143 also becomes deenergized.

and the power magnet of sequence switch 208, to grounded battery, for moving this sequence switch out of position 16 and into position 18. A circuit is now closed from 5 grounded battery, through the winding of the magnet 251, conductor 252, and the upper right-hand and lower left-hand contacts of sequence switch spring 218, to ground. The magnet 251 by attracting its armature 10 presses brush rod 214 against the roller 253, constantly rotating in the direction indicated by the arrow, whereby the connector is released to normal. As soon as a brush 15 254, carried by the brush rod, reaches a normal conducting segment 255, a circuit is closed from ground, through the lower contact of sequence switch spring 218, conductor 219, brush 254, conducting segment 255, conductor 256, the lower left-hand contact 20 of sequence switch spring 207, and the power magnet of sequence switch 208, to grounded battery, for moving the sequence switch out of position 18 and into position 1. The magnet 251 becomes deenergized, the relay 25 226 being deenergized since the sequence switch 208 left position 16.

In case the desired subscriber's line is busy the potential on test terminal 225 and multiples thereof is reduced. For this reason, upon the engagement of terminal 225 by wiper 229, the marginal relay 226 does not receive sufficient current to permit its energization. When, therefore, the sequence switch 208 reaches position 14, in the above described manner, due to the deenergized condition of relay 226, no circuit will be closed through the lower right-hand contact of sequence switch spring 207, and thus the sequence switch stops in position 14. A circuit is now closed from ground, through the lower armature and back contact of the test relay 226, a sequence switch contact 257, conductor 252, and the winding of magnet 251, to grounded battery. The magnet 251 40 causes the release of the connector in the same manner as above described and when the brush 254 engages the normal conducting segment 255, the circuit through the lower left-hand contact of sequence switch spring 207 is closed and the sequence switch 208 45 driven out of position 14 and into position 17. A circuit is now closed from ground through a constantly operating interrupter 258, a resistance 270, the upper contact of sequence switch spring 227, conductor 223, selector wiper 131, sequence switch spring 148, the lower contact of relay 144, conductor 103, the ring contacts of jack 106 and plug 105, the winding of the supervisory relay SR' and the secondary winding of the repeating coil, to grounded battery. The supervisory relay SR' is intermittently energized and deenergized and causes thus the 50 55 60 65 70 75 80 85 90 95 100 105 110 115 120 125 130 135 140 145 150 155 160 165 170 175 180 185 190 195 inform the calling subscriber of the busy condition of the desired line and causes the restoration of the selector switch 115 in the same manner as above described.

Establishment of a full-automatic connection. 70

A subscriber whose station is indicated at 300 may control the establishment of connection between his station and station 200 75 through a line finder 301, a selector 302 and the connector 210. Cord circuits, such as the ones shown in Fig. 3, terminate at one end with the line finding switch 301, and at the other end with 80 the selector switch 302, both being of the panel type, as previously stated. Upon the initiation of a call by any one of a plurality of full automatic subscribers whose lines terminate in the panel bank traversed by the brushes of the switch 301, a preselected switch 301 is caused to immediately move to and select the terminals of the calling line. The calling subscriber will thereupon actuate the sending device at his station to register the designation of the line wanted in the register sender which was preselected and operatively associated with the line finder prior to its actuation.

The setting of selector 302 is accomplished 95 in substantially the same manner as the setting of selector 115, with the difference that the sender is set for operation under the control of the calling subscriber. During the movement of selector 302 the sender will receive impulses in accordance with its setting.

The selector 302 is set to seize the connector 210 through conductors 270, 271 and 272.

Upon the seizure of the connector, the relays 202 and 204 operate in substantially the

same manner as above described and, under the control of the sender shown in Fig. 3,

the connector switch is set to seize the called subscriber's line. If this line is idle, then the 110 sequence switch 208 is arrested in position 16 and ringing current is applied to the called subscriber's line from a source (not shown) associated with the selector 302.

Upon the removal of the receiver at the called station, the supervisory relay 304 becomes energized and closes a circuit for energizing a relay 305, whereupon this relay locks up through a circuit closed through its right-hand front contact and arm

contact 306 upon the deenergization of the supervisory relay 304, a circuit is closed from ground through the armature and back contact of this relay, the left-hand 5 front contact and armature of relay 305, the line finder 301, and the winding of a magnet 307 to grounded battery. The magnet 307, upon energization, actuates a well-known message register.

10 If the desired line is found busy, then the connector 210 is released in the above described manner in position 14 of sequence switch 208, and the sequence switch 208 is moved into position 17. Due to the fact 15 that the selector 302 did not engage the conductor 223 leading to the connector 210, in position 17 of the sequence switch 208, the ground intermittently applied to this conductor 223 will not affect the supervisory 20 relay 304. Should the supervisory relay be operated under the control of interrupter 258, the magnet 307 would be actuated to operate the message register, although the desired line was busy. In position 17 of 25 the sequence switch 208, a tone is applied from a source 273 through an induction coil 274, condenser 275, the lower contact of a sequence switch spring 276, conductor 271, and thence through the repeating coil 310 30 to the calling subscriber's station, indicating to him the busy condition of the line, whereupon he causes the releasing of the line finder and the selector by the hanging up of his receiver.

35 What is claimed is:

1. In a telephone system, two groups of lines, a called line, means for extending a calling line of either group to said called line, two characteristic busy signaling 40 means, and means depending on the group to which an extended calling line belongs for operatively associating therewith a certain one of said signaling means.

2. In a telephone system, groups of lines, 45 a called line, a switch for connecting any one of said lines when calling to the called line when idle, two busy signaling apparatuses of different character associated with said switch, means for connecting only 50 one of said apparatuses to calling lines belonging to one of said groups, and means for connecting only the other apparatus to calling lines belonging to the other group.

3. In a telephone system, groups of lines, 55 a called line, a selectively operable switching device operable to seize said called line, operator controlled means for extending calling lines of one group to said device,

subscriber controlled means for extending calling lines of the other group to said device, two characteristic busy signaling apparatuses associated with said device, means for associating only one of said apparatuses with extended calling lines of one group, and means for associating only the other apparatus with extended calling lines of the other group.

4. In a telephone system, a plurality of lines of various character, another line, switching means, means for actuating the 70 same for connecting any one of said plurality of lines to said other line, a signaling device associated with said switching device, means operative in response to the actuation of said switching means to connect a line of a certain character for effectively associating said signaling device with said last mentioned line, and means for preventing the operation of said last mentioned means when said switching means is actuated to connect a line of a certain other character.

5. In a telephone system, two groups of lines, a selectively operable switch, lines terminating thereat, means for rendering said last mentioned lines busy, means for extending any of the lines of said groups to said switch, a subscriber's calling device associated with each line of the first group, an operator's sender, means for associating 90 said sender with an extended line of the other group, means alternatively operable by a calling device and said sender for causing said selector switch to seize a desired idle line terminating thereat, means operative in response to the busy condition of said 95 desired line for preventing the successful operation of said last mentioned means, a constantly operating interrupter and a constantly operating tone producing device associated with said selectively operable 100 switch, means operative in response to an unsuccessful operation of said switch for simultaneously preparing said interrupter and tone producing device for connection to 105 a line extended to said selectively operable switch, means for connecting only said tone producing device to an extended line belonging to the first group, and means for connecting only said interrupter to an extended line belonging to the second group.

In witness whereof, I hereunto subscribe my name this 28th day of December A. D., 1916.

ALBEN E. LUNDELL.
